VARIABLE AREA, PUSH-PULL SOUND RECORDING SYSTEM

John G. Frayne, Pasadena, Calif., assignor to
Western Electric Company, Incorporated, New
York, N. Y., a corporation of New York

Application May 1, 1947, Serial No. 745,147

1 Claim. (Cl. 179—100.3)

1

This invention relates to film sound recording and particularly to the recording of push-pull sound tracks on photographic film.

It is an object of this invention to provide a method and apparatus for recording a bilateral variable area, class B push-pull sound track on a recording film.

It is a further object of this invention to provide a variable area recording system incorporating an improved light valve of simple construction capable of modulating the recording light beam in a manner to produce on a recording film a class B variable area, push-pull negative sound track.

A feature of the invention lies in the provision in a sound recording system of a single modulating device comprising three flat conducting ribbons immersed in a constant magnetic field and spaced transversely in the recording system to substantially completely mask the recording light beam, the two outer ribbons being responsive to the sound modulated currents to move together in parallel relation in one direction while the center ribbon moves simultaneously in the opposite direction in response to the same sound currents.

It is common practice in making an original sound track to record the sound on the recording film in the form of a push-pull sound track. It has been found desirable in many instances to utilize class B type push-pull recording for the reason that this method produces, without the use of noise reduction systems and apparatus, a film having a very high signal to noise ratio by virtue of the fact that practically no transparent areas exist on the print except those produced by the signal currents which actuated the modulating device.

A bilateral, variable area, class B push-pull sound track is well known and systems employing a modulating device incorporating conducting ribbons responsive to the sound currents, have been developed heretofore for recording this type sound track. However, in the earlier systems it was found necessary to employ two pairs of conducting ribbons, one pair for each track, and to employ a half-wave rectifier in the circuit from the sound source to each of said pair of ribbons to insure the response of one pair to the positive half-wave and the other pair to the negative half-wave of the sound current.

In accordance with the present invention, a bilateral variable area, class B push-pull sound track is obtained in a recording system having optical means producing a rectangular light beam, by means of a single light valve having three flat

2

conducting ribbons disposed with their longer axes parallel to the longitudinal axis of the film and transversely spaced in the system to form a mask for the light beam. Connections from the source of sound modulated currents are made in a manner to cause the sound currents to flow in the same direction in the two outer ribbons and in the opposite direction in the center ribbon, thus producing alternate unmasking of the light beam on opposite sides of the center ribbon.

The invention will be more readily understood from the following description when read in connection with the accompanying drawing, in which:

15 Fig. 1 is a diagrammatic representation of a sound recording system incorporating this invention;

Fig. 2 is a fragmentary enlarged view of the light valve of Fig. 1, showing the position of the 20 conducting ribbons with respect to the pole piece aperture;

Fig. 3 is a side elevation of the pole piece and ribbons shown in Fig. 2; and

Figs. 4 and 5 are respectively enlarged negative 25 and positive film records obtained by the recording system of this invention.

In Fig. 1, the recording system in accordance with this invention comprises a light source 1, condenser lens system 2, light valve 3, objective lens 4 and recording film F.

Light valve 3 comprises three flat conducting ribbons 5, 6 and 7 immersed in the constant magnetic field produced by permanent magnets 8 and 9 and disposed in front of aperture 10 in pole 35 piece 11.

Light from source 1 is focussed by lens system 2 on aperture 10. Lens 4 focusses an image of the ribbons 5, 6 and 7 on the sound track area 12 of film F. It will be seen in Fig. 2 that for proper adjustment before operation, the center ribbon 6 covers or masks approximately one-half of the aperture 10 while ribbons 5 and 7 each cover or mask approximately one-quarter of this aperture at the ends thereof. The three ribbons 45 are the same width and one-half of each of the ribbons 5 and 7 extend beyond the ends of the aperture. For 100 per cent modulation of the ribbons they each move in either direction a distance no greater than one-quarter the length of 50 the aperture 10 so that the ends of this aperture are never unmasked by the outside edge of either ribbon 5 or 7.

Referring to Fig. 3, it will be seen that ribbons 5 and 7 are coplanar while ribbon 6 is disposed 55 in a separate, parallel plane. This arrangement

of the ribbons permits the center ribbon 6 to move in its own plane in a direction opposite to the direction of movement of outer ribbons 5 and 7 to produce alternate unmasking of the aperture 10 on opposite sides of ribbon 6. Separation of the ribbon planes may be in the order of one mil. A sharp image of all three ribbons may be obtained at the film plane by employing an objective lens 4 having a depth of field approximately the same as the distance separating the two ribbon planes.

For the sake of clarity in the drawings, a slight separation is shown between the ribbons. It is apparent, however, that these ribbons may be adjusted at zero modulation to just completely mask the aperture 10, under which condition the sound track recorded will be strictly a class B type track. If for any reason it is found desirable to provide a small initial opening between the ribbons, a certain amount of class A recording will be obtained at very low amplitudes. The amount of class A recording would not, however, exceed the width of the initial opening, that is, it would be confined approximately to the width of the exposed area 15, Fig. 4, which appears as a clear area 16 in the positive print of Fig. 5.

Referring to Fig. 1, a microphone 17 is disposed adjacent the source of sound to be recorded. The sound modulated signal wave from this microphone is amplified in amplifier 18 and supplied to the primary of transformer 19. Lead 20, from one terminal of the secondary of transformer 19, is connected to the upper end of each ribbon 5 and 7. The other end of each ribbon 5 and 7 is connected to the lower end of ribbon 6. The upper end of ribbon 6 is connected by lead 21 to the other terminal of transformer 19.

A resistance 22 is placed in shunt with ribbon 6 and is of such value that the current in ribbon 6 is equal to the current in either of the ribbons 5 or 7.

Arrows S in Fig. 2, indicate the direction of flow of the current in the outer ribbons 5 and 7 relative to the direction of flow of the same current in ribbon 6 during one part of the current cycle. The direction of flow indicated will, of course, be reversed for the rest of the current cycle. Under the influence of the constant magnetic field at right angles to the direction of the current, the two outer ribbons will always move together in the same direction and opposite to the direction of motion of the center ribbon. Arrows D, Fig. 2, indicate the relative direction of

movement of the ribbons for one part of the current cycle.

Alternate unmasking of the aperture 10 on opposite sides of the ribbon 6 will produce exposed areas 25 and 26 on the processed negative shown in Fig. 4. Each exposed area represents a half-wave of the recorded signal. These exposed areas will appear as clear areas 27 and 28 respectively, on a processed positive print as shown in Fig. 5.

10 Applicant's invention provides a novel method and system of apparatus whereby a bilateral variable area, class B push-pull sound track may be efficiently recorded on photographic film by a single modulating device directly connected in a novel manner to a source of sound currents.

What is claimed is:

15 In a sound film recording system including means for producing a rectangular beam of light and means for projecting said beam of light toward said film with its longer axis transverse to said film, a light valve comprising a pair of coplanar, parallel conducting ribbons immersed in a constant magnetic field and spaced so that their inner edges define the narrow edges of said 20 rectangular beam of light and a third parallel conducting ribbon disposed in said magnetic field in a separate parallel plane to mask the portion of said light beam between said first-mentioned pair of ribbons, the corresponding ends of all 25 said ribbons at one end thereof being electrically connected together, means forming an image of all said ribbons at the plane of said film, a source of modulated electric currents, an electrical connection from one side of said current source to 30 the free end of each of said pair of coplanar conducting ribbons and a connection from the other side of said current source to the free end of 35 said third conducting ribbon.
